DEVICE FOR CLOSING A BAG

Martin de Botelho, New York, N. Y.

Application August 5, 1937, Serial No. 157,485

4 Claims. (Cl. 150—3)

My invention pertains to devices for closing bags, pouches and other receptacles, and is herein illustrated in its application to a relatively small bag suitable as a container for a perfume bottle.

The principal object of my invention is to provide simple and novel means for gathering and holding together the edges of the open end of a bag.

10 Another object is to provide simple and efficient means for drawing the open end of a bag through a member which will retain it in a gathered or closed position.

15 An additional object to which my invention is directed is the provision of means for keeping a closing member in convenient association with the bag with which it is to be used.

20 Certain additional objects, together with the many advantages of my novel construction, will be disclosed in the ensuing parts of my specification.

With reference to the accompanying drawing:

Fig. 1 represents a front elevation of a bag with the closing device in an inoperative position.

25 Fig. 2 is also a front elevation of the bag, but with its open end bent forward and in a partially closed position.

30 Fig. 3 shows the bag in completely closed position with the closing device in its final operative position.

The illustrative embodiment of my invention comprises a rectangularly shaped bag 10 which is open at its upper end. Any suitable flexible material may be used in constructing the bag 10.

35 A cord or loop member 12 of a flexible nature has one end connected to a side of the bag 10 at a point 14 near the top or open end. The other end of the cord 12 may be connected to the bag 10 in a lower position 15, on the same side.

40 An identical cord or loop member 13 is connected similarly to the bag 10 at points 16 and 17 on the opposite side.

45 The cords 12 and 13 are threaded or passed loosely through a ring 11 in the manner indicated in Fig. 1 of my drawing. Means for retaining the ring in permanent association with the bag are provided by the connections 15 and 17 between the lower ends of the two loop members and the bag. While metal is a preferred material for the ring 11, celluloid, rubber, synthetic resin or other similar substances may be utilized.

50 When the parts of the cords 12 and 13 below the ring 11 are pulled in opposite directions,

such as by the thumb and forefingers of a pair of hands shown in Fig. 2, the extremities of the bag opening adjacent the points 14 and 16 are pulled progressively through the ring 11 (Fig. 2). This action gathers the other portions comprising the opening of the bag 10 to such an extent that they too readily follow the said extremities through the ring 11. After the ring 11 has moved downwardly a short distance the portions of the bag above the ring 11 will be expanded 5 or spread by continued pulling so as to retain said ring.

Fig. 3 shows the bag 10 in its completely closed position. It will be appreciated that the size of the ring 11 is determined by the amount of the 15 bag material which must be circumscribed to effect a closure.

The following is a description of a convenient manner of operating my device:

a. Gather the cords 12 and 13 below the ring 20 11, take one between the thumb and index finger of each hand, and pull.

b. Slide thumbs and index fingers closer to ring 11, and pull until the bag is closed.

By using a pair of cords or loop members, I 25 attain several novel functions which are not comprehended by any prior structures of which I am aware: The ring is held in a convenient and centered position with respect to the bag prior to being moved to its operative position. Two 30 opposite extremities of the bag opening are guided smoothly through the ring.

Although the invention has been described as embodied in a particular bag construction, it should be understood that the invention is not 35 limited in the scope of its application to any one form of receptacle.

Having described my invention, what I claim as new and desire to secure by Letters Patent of the United States is:

1. A bag provided with an opening and having a closing device which comprises a pair of cords, an end of one cord being connected to the bag near an extremity of the opening and an end of the other cord being connected to the bag near 45 the opposite extremity of said opening, a ring threaded on said cords, and means for retaining the ring in association with the bag.

2. A bag provided with an open end, a closing device comprising a pair of cords and a ring 50 through which said cords are passed loosely, said cords each being attached by an end to opposite extremities of the open end of the bag, and means for retaining the ring in association with the bag.

3. A bag provided with an open end and having a closing device which comprises a pair of loop members and a ring through which said loop members are threaded, one loop member being connected to a side of the bag at an extremity of the open end thereof and at a lower point on the same side, and the other loop being similarly connected with the opposite side of the bag.
4. In a bag having an opening at one end, a closing device comprising a ring and two lengths

of cord which pass through said ring, each of said lengths of cord originating at an extremity of the bag opening and the aperture of said ring having a peripheral length sufficient to circumscribe the open end of the bag when the adjacent portions of the bag are gathered into a closing position, and means for retaining the ring in association with the bag.
